[57] CLAIM

The ornamental design for an industrial work table, as shown and described.

DESCRIPTION

FIG. 1 is a top plan view of an industrial work table illustrating my invention;

FIG. 2 is a front elevational view thereof;

FIG. 3 is a rear elevational view thereof;

FIG. 4 is a side elevational view taken from the right side of FIG. 1, the left side being the mirror image thereof; and

FIG. 5 is a bottom plan view thereof.

FIG. 1

FIG. 2

FIG. 3

FIG. 4

FIG. 5
